UNITED STATES PATENT OFFICE

2,497,692

POWDER COMPACT

Rose Schulfer, Stevens Point, Wis.

Application October 15, 1947, Serial No. 779,876

1 Claim. (Cl. 132—82)

1

This invention relates to new and useful improvements and structural refinements in powder compacts or vanity cases, as they are sometimes called, and the principal object of the invention is to provide a device of the character herein described which includes in its construction a powder receptacle and a powder puff, matters being so arranged that powder may be dispensed from the receptacle onto the powder puff in proper quantities, when so desired.

A further object of the invention is to provide a powder compact which, by separating the powder receptacle from the powder puff, prevents powder from gathering on a mirror with which the compact is equipped, and which, in conventional compacts, is usually disposed immediately adjacent the powder-coated puff.

Another object of the invention is to provide a powder compact which is simple in construction, pleasing in appearance, and which may be easily and conveniently used.

A still further object of the invention is to provide a powder compact which will not readily become damaged and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a perspective view of the invention, showing the same in an open position;

Figure 2 is a cross sectional view of the powder compact in a closed position;

Figure 3 is a cross sectional view, taken substantially in the plane of the line 3—3 in Figure 2; and

Figure 4 is a fragmentary underside plan view of the powder receptacle and valve used in the invention.

Like characters of reference are employed to designate like parts in the specification and throughout the several views.

Referring now to the accompanying drawings in detail, the invention consists of a powder compact designated generally by the reference character 10, the same embodying in its construction a suitable container 11 provided with an openable cover 12 which is hingedly secured to the container as indicated at 13.

If desired, a suitable catch 14 and a finger piece 15 may be provided on the container 11 and cover 12 respectively, so that opening and closing of the cover is facilitated and means for openably

retaining the cover in its closed position are present, as will be clearly apparent.

A suitable mirror 16 is provided on the inner surface of the cover 12, and the container 11 is adapted to removably receive in the bottom thereof a conventional powder puff 17.

The essence of novelty in the invention resides in the provision of a powder receptacle 18 in the container 11, the receptacle 18 being configurated substantially as shown and being mounted between the powder puff 17 and the mirror 16, as will be clearly apparent from the accompanying drawings.

The receptacle 18 is provided with a removable filler block 19 which is preferably located in the upper surface or wall 20 of the receptacle, while the bottom 21 of the receptacle is formed with a powder dispensing opening 22.

It will be observed that the opening 22 is disposed immediately above the puff 17, and means are provided for opening and closing the opening 22, said means consisting of a valve plate 23 which is pivoted to the bottom 21 of the receptacle 18, as indicated at 24.

25 The plate 23 projects somewhat beyond the front wall 25 of the receptacle 18 and terminates in a finger piece or handle 26, so that when the invention is placed in use powder (indicated at 27) may be dispensed from the receptacle 18 through the opening 22 by simply swinging the plate 23 from one side to the other, so as to open and close the opening.

Needless to say, if the amount of powder which is so dispensed during one oscillation of the plate 35 23 is insufficient, the swinging or oscillatory actuation of the plate 23 may be repeated, as desired.

By virtue of this arrangement, a proper amount of powder will be deposited onto the puff 17, and at the same time it should be pointed out that the receptacle 18 will function as a barrier, so to speak, separating the powder-coated puff from the mirror 16, so that the possibility of the powder coating the mirror will be minimized, if not completely eliminated.

45 It is believed that the advantages and use of the invention will be clearly understood from the foregoing disclosure, and accordingly, further description thereof at this point is deemed unnecessary.

50 Having described the invention, what is claimed as new is:

In a powder compact, the combination of a substantially rectangular container having an open front and an open top, a unitary cover for said open front and top hinged to the upper edge

of the back wall of the container, a powder receptacle secured to said back wall and disposed in the container in spaced relation to the bottom of the latter, the front wall of said receptacle being spaced rearwardly from the front portion of said cover, the bottom of said receptacle having a dispensing opening, a closure member for said opening provided under the bottom of the receptacle, and a finger piece provided on said closure member and extending forwardly in said container beyond the front wall of the receptacle, whereby the closure member may be conveniently actuated upon opening of said cover.
